UNITED STATES PATENT OFFICE.

OTTO A. HEPPES, OF LA GRANGE, ILLINOIS, ASSIGNOR TO THE FLINTKOTE COMPANY, OF BOSTON, MASSACHUSETTS, A CORPORATION OF MASSACHUSETTS.

ROOFING.

Application filed September 8, 1923. Serial No. 661,573.

This invention relates to roofing more particularly of somewhat flexible material such as is commonly made of fibrous sheet material saturated with waterproofing material, 5 as asphalt, and coated with high melting point asphalt, with or without a surfacing of granular material such as crushed slate. When such material is laid in superposed overlapping courses any depending tabs or 10 projections exposed to the weather are liable to become raised from the roof as by wind or accidental curling or warping of the material, impairing the appearance of the roof and if pronounced, its weatherproofing capabilities also. The tabs or projections are also liable when raised to be torn off or otherwise damaged. This action is particularly liable to occur when comparatively large shingle units are being used, as for example, 15 when square shingles are laid diagonally on the roof exposing to the weather all but comparatively narrow portions along their upper converging edges.

According to the present invention, therefore, each shingle is so formed that its depending corner portion may interlock with the adjacent shingle where the latter is quite directly made fast to the roof.

For a more complete understanding of this invention, reference may be had to the accompanying drawings in which

Figure 1 is a plan of a shingle formed according to this invention.

Figure 2 is a fragmentary plan of a roof showing the shingles of Figure 1 laid thereon.

Figure 3 is a detail illustrating interfitting portions of a pair of adjacent shingles slightly separated.

Referring to these drawings, 1 indicates a shingle element preferably of flexible sheet material of polygonal form, as herein shown it being square. One corner, herein shown as the left hand corner when the shingle is laid diagonally on the roof, is slotted inwardly 40 as at 2. This slot extends inwardly from this corner substantially horizontally so that it bisects the angle formed by the converging upper edge 3 and lower edge 4 of the unit. The other lower edge 5 of this unit has cut 45 therefrom near its apex with the side 4 a slot 6 substantially parallel with the slot 2 and extending in the opposite direction thereto, this slot being at an angle to the perpendicu-

lar to the side 5 and being spaced from the slot 2. The slot 2 may be regarded as extending inwardly from the side 4 of the shingle element adjacent to the side 5 and also as extending inwardly from the opposite side 3 and at an angle to the perpendicular to each of these sides. The shingles are laid as shown in Figures 2 and 3, the slot 6 of one shingle interlocking with the slot 2 of the diagonally positioned shingle of an underlying course, the portion 7 below the slot 6 underlying the portion 8 below the slot 2 and the edges 4 and 5 of the various courses of shingles being respectively in diagonal alignment as more clearly illustrated in Figure 2. When laid the fastening elements, such as nails, by which the shingles are fixed to the roof, are driven in adjacent to the upper converging edges 3 and 9 where they will be overlaid by the succeeding course, consequently the slots 2 of the shingles are closely adjacent certain of said fastening elements and hence the adjacent shingle portions are securely held down to the roof. The depending corners of the units of the succeeding course are thus interlocked with portions of the previous course closely held to the roof, consequently they also are held firmly in position so that they can not be raised upwardly from the roof, the shingles interfitting and engaging each other in pairs.

Having thus described an embodiment of this invention it should be evident that various changes and modifications may be made therein without departing from its spirit or scope as defined by the appended claims.

I claim:

1. A roofing element comprising a polygonal shaped piece of sheet material having an open-ended slot extending inwardly from the apex of one corner and a slot extending inwardly from one side.

2. A roofing element comprising a polygonal shaped piece of sheet material having a slot extending inwardly from one corner and a slot extending inwardly from one side, said slots being substantially parallel.

3. A roofing element comprising a polygonal shaped piece of sheet material having a slot extending inwardly from one corner and a slot extending inwardly from one side, said slots being substantially parallel and at an angle to the perpendicular to said side.

4. A roofing element comprising a square piece of sheet material having a slot extending inwardly from one corner and a slot extending inwardly from one side at an angle 5 to the perpendicular to said side.
5. A roofing element comprising a square piece of sheet material having a slot extending inwardly from one corner and a slot extending inwardly from one side adjacent to 10 one corner at an angle to the perpendicular to said side.
6. A roofing element comprising a square piece of sheet material having a slot extending inwardly from one corner and a slot extending inwardly from one side at an angle 15 to the perpendicular to said side, said slots being substantially parallel to each other.
7. A roofing element comprising a square piece of sheet material having a slot extending inwardly from one corner and a slot extending inwardly from one side adjacent to one corner at an angle to the perpendicular 20 to said side, said slots being substantially parallel to each other.
- 25 8. A roofing element comprising a piece of sheet material having oppositely disposed substantially parallel sides, said piece having a pair of open-ended slots extending obliquely inward from different sides thereof in 30 opposite parallel directions.
9. A plurality of shingles each having four corners with a slit projecting inwardly from one corner and a second slit projecting inwardly from a second corner, said shingles 35 being adapted to be laid in rows with their upper and lower edges registering and with said slits interlocking.
10. A plurality of shingles each having four corners with a slit projecting inwardly from the point of a corner at one end of the 40 shingle, and a slit projecting inwardly from a second corner, but spaced from the point of said second corner, said shingles being adapted to be laid in rows with their abutting edges registering, with said end of each shingle lapping over an end of an adjacent shingle, and with the two slits interlocking.
11. A plurality of shingles each having four corners with a slit projecting inwardly from one corner and a second slit projecting 45 inwardly from a second corner, said slits both extending in directions oblique to the sides of the shingles, said shingles being adapted to be laid in rows with their upper and lower edges registering and with said slits interlocking.
12. A plurality of rectangular shingles each having four corners with a slit projecting inwardly from the point of a corner at one end of the shingle and a parallel slit projecting inwardly from a second corner but spaced from the point of said second corner, said shingles being adapted to be laid in rows with their abutting edges registering, with said end of each shingle lapping over an 50 end of an adjacent shingle, and with the two slits interlocking.

In testimony whereof I have affixed my signature.

OTTO A. HEPPEs.
